TRAIN CONTROL

Application filed March 17, 1922. Serial No. 544,561.

This invention relates to automatic train control systems, and more particularly to such systems characterized by the communication of the control impulses or influences from the trackway intermittently at separate control points along the track.

In certain types of brake control apparatus employed in connection with automatic train control systems for regulating train movement, some form of restriction upon the movement of the train is initiated or set up whenever danger conditions exist and it is desired to compel the train to slow down, such restriction persisting or continuing until proper for the train to resume its normal running speed. For example, the brakes of the locomotive or other vehicle may be governed by the cooperation of a speed responsive device and a changeable permissive speed device, these devices cooperating, when initiated or placed in condition for operation, to cause an automatic brake application unless the vehicle maintains speeds less than certain successively lower permissive speeds prescribed by the permissive speed device; or the automatic brake application may be dependent on pressure responsive devices associated with the air brake equipment and manifesting whether or not the brakes are applied; or the automatic brake application may be dependent upon the position or condition of some other means manifesting that the train is, or is not, being controlled in the manner desired, and that a brake application should or should not, be automatically made.

For the proper control of such systems of the type above indicated, which may be said to be cyclic in their nature, it becomes desirable to provide, not only an initiatory or starting influence from the trackway dependent upon traffic conditions, but also a suitable restoring or resetting influence, likewise dependent upon traffic conditions, so that the restoration or resetting of the train control mechanism, after its operation has been initiated or started, will be obtained automatically and consequently will assure that the train will not be relieved from the desired restrictions imposed upon it by the

continued activity of the train control mechanism, until it is safe to do so.

The control impulses or influences from the trackway to the moving vehicle, mentioned above, are preferably produced inductively, that is, through an intervening air gap and without physical contact; and for the proper and safe control of a cyclic type of train control mechanism, the initiating and resetting influences should be of two distinctive characters. Also, the initiating or knock-down influence communicating means should be constructed on the closed circuit principle, that is, so that any failure will be on the side of safety; whereas the means providing the pick-up or resetting influence, such influence being a favorable control allowing the train to resume speed, should be constructed on the open circuit principle, that is, such that any failure of the battery, breakage of wires, and the like will prevent, rather than cause the communication of the resetting influence.

In addition to the requisites above noted, for practical operation it is desirable to make provision such that the locomotive, motor car, or other vehicle may be properly controlled when traveling either end ahead in the normal direction of traffic and not controlled when running either end ahead opposite to the normal direction of traffic.

Generally speaking, the primary objects and purposes of the present invention are to provide a system of intermittent inductive influence communicating means conforming with and meeting the requirements above indicated; and various specific objects, advantages, and characteristic features of the invention will be pointed out as the description progresses.

In the accompanying drawings, Figure 1 shows in a simplified and diagrammatic manner a typical block signal system, together with the track devices and circuits constituting one embodiment of the invention; and

Fig. 2 is a diagrammatic and simplified view of car apparatus conforming with the present invention, the illustration shown being intended to make it easy to understand the invention, rather than show the particu-

lar construction and arrangement of parts preferably employed in practice.

Track equipment.—It is contemplated that the train control system of this invention will be used as a supplement or as an adjunct to some suitable form of automatic, or manually controlled block signal system; and while the system may be used without such trackway signals, there has been selected for illustration in Fig. 1, the application of the train control system to a simple automatic block signal system. Various arrangements of trackway circuits for providing the desired control of block signals are well-known, and it should be understood that the arrangement shown in Fig. 1 is merely typical. The fixed signals A, although they may be color light, position light, or any suitable type of signal, have been shown conventionally as three-position semaphore signals, and without attempting to illustrate their well-known structure and control circuits.

Referring to Fig. 1, the track rails 1 of the railroad track are divided by insulated joints 2 into blocks in the usual way, one block I with the adjacent ends of two other blocks H and J being shown. Since the parts and circuits associated with the various blocks are the same, they will be given the same reference characters with distinctive exponents as a matter of convenience. Each of the blocks is provided with a track battery 3, a track relay 4, and a line or distant relay 5, the same as in ordinary block signal systems. The line relay 5 of each block is controlled by the track relay of the block next in advance. The energizing circuit for the relay 5 of the block I may be readily traced on the drawings, the conventional designations B and C being used in this and other circuit showings to indicate connections to opposite sides of a battery or other suitable source of electrical energy.

The track elements or devices of the impulse communicating means are alike in their structure, and each comprises a U-shaped core 6 of soft iron laminations, which is preferably provided with enlarged pole pieces; and on the back yoke of this core, is a coil 7 which is included in a traffic controlled circuit of low resistance, in a manner to be explained later.

To produce the initiatory, danger or knock-down influence, one of the track elements above described, is associated with each block and is located on one side of the center line of the track, with respect to the normal direction of traffic. In the particular illustration of Fig. 1, the knock-down element KD is located on the righthand side of the track and near the entrance to its corresponding block. It should be understood, however, that this knock-down element KD may be located at any desired point with respect to the entrance end of its corresponding block, that

is, it may be at the exit end of the next block in the rear, or at an intermediate point, or in the first part of the corresponding block itself, the space between said knock-down element and the exit end of the corresponding block being braking distance or a distance suitable for the operation of the particular type of cyclic train control mechanism employed. The knock-down element of each block has its coil 7 in a circuit of low resistance controlled by a front contact 8 of the corresponding line relay 5, so that if the next block in advance is occupied, said coil 7 is open circuited, whereas, if said next block in advance is not occupied, said coil is included in a closed circuit of low resistance. In this connection it is understood that in the system under consideration it is contemplated that a train should not be permitted to make a back-up move or in any other way move against the normal direction of traffic for which the system is signalled; for if this were permitted less than braking distance would be available to an approaching train, and the system would be unsafe.

For the purpose of transmitting the desired resetting, proceed or restoring impulse two track devices, the same in structure as the knock-down device KD, are disposed in a predetermined relation with respect to each other corresponding to the disposition of the car elements cooperating therewith. These resetting or pick-up track elements, designated PU are in effect a pair of the initiatory knock-down devices KD, which are connected together in a cooperative relation to produce the desired resetting influence. As shown, the track elements PU are located directly opposite each other on opposite sides of the track, but these elements may be staggered lengthwise of the track depending upon the disposition of the car elements, the preferred arrangements being that in which the two car elements on opposite sides of the locomotive will pass simultaneously over the two pick-up elements PU. The pick-up elements PU are located at the exit end of the block, and are controlled by the track relay of the block next in advance. Additional pairs of pick-up elements PU, controlled in the same way may be disposed at intermediate points in the block to provide for intermediate release. In each case, the pick-up elements PU are located so that they will be passed before the train enters the block controlling them. Also, in advance of each of one or more pick-up elements, there must be a knock-down element KD, in order to assure initiating or starting the operation of the train control mechanism again, after being once reset, if there are danger conditions in the next block in advance of the one the train is about to enter.

When clear conditions in the controlling

block exist, and it is proper to cause an automatic reset, the coils 7 of the pick-up track elements PU are connected in series in a closed circuit, this circuit in the case of the elements PU at the entrance to the block I being as follows:—commencing at coil 7 of the upper element PU in Fig. 1, wire 9, armature 10 of track relay 4 and its front contact, wire 11, armature 12 of track relay 4 and its front contact, wire 13, coil 7 and wires 14 and 15, back to the coil 7 of the uppermost track element.

The pick-up track elements PU are individually connected in a circuit of low resistance when the corresponding control block I is occupied, this circuit in the case of block I being traced as follows:—commencing at coil 7 of the upper track element, wire 9, armature 10 and its back contact, wires 16, 17 and 15 back to the same coil. For the coil of the other track element the closed circuit may be traced commencing at said coil, wire 13, armature 12, and its back contact, wires 18, 17 and 14.

Thus, the pick-up track elements PU are connected in series under clear traffic conditions, and are individually connected in a circuit of low resistance under dangerous traffic conditions. In this connection attention is directed to the fact that there is little tendency for current to flow through the two coils 7 of the track way devices PU in series when they are both short-circuited by the back contacts 10 and 12 of track relay 4, and the pick-up relay PR will not respond to the small amount of current that may be caused to flow in the second of these coils 7 during the passage of the train containing said relay PR. In other words, the coils 7 of the track way device PU are effectively short-circuited.

From the foregoing explanation, it can be seen that the knock-down track element KD at the entrance to any block is open-circuited when the next block in advance is occupied, and close-circuited when said block is clear; and that the pick-up track elements PU at the exit end of each block are connected in a series circuit when the next block in advance is clear, and are disconnected from each other and individually connected in a closed circuit of low resistance when said next block in advance is occupied.

Car equipment.—In Fig. 2 of the drawings have been illustrated diagrammatically the car apparatus and circuits of the present invention. In this arrangement, three two-wire bus bars, or bus circuits, are provided. These bus circuits may conveniently be called the primary bus *p*, the secondary bus *s* and the reset bus *r*. Two identical car elements, one located on the right side when facing toward the pilot end of the vehicle and designated R, and the other located on the other side of the vehicle and designated L are provided. Each of these car elements comprises

a U-shaped core 20 of a high grade transformer iron, which has a primary coil *P* on one leg and a secondary coil *S* on the other, the legs of these elements being terminated in enlarged pole pieces 21. An automatic double throw reversing switch or circuit controller is provided which will connect the primary coil *P* of the car element R to the primary bus *p*, connect the secondary coil *S* of the element R to the secondary bus *s*, and will connect the coils *P* and *S* of the car element L in series to the reset bus *r*, when the locomotive is running pilot ahead, and will reverse these elements in the respective circuits when the locomotive is running tender ahead.

This double-throw circuit controller comprises a long operating rod 22 having connected thereto but insulated therefrom movable switch blades 23, 24, 25, 26, 27, 28, 29 and 30, and having one end connected to a collar or ring 31 loosely mounted on an axle 32 of the locomotive or other vehicle, and having an operating arm 33 extending therefrom to which the operating rod 22 is pivotally fastened. The inside circumference of the ring is provided with a notch in which is contained a brake-shoe 34 which is held against the axle 32 by a compression coil spring 35. On each side of the operating arm is provided a stop pin to limit its movement in each direction. As the vehicle is moving toward the right, the axle turns the arm to position shown against the stop pin 36; and as the direction of movement of the vehicle is changed, the arm is automatically shifted to the other position against the other stop pin 37.

The control devices on the vehicle adapted to be actuated by the car elements R and L, comprise a main control relay D, which is constructed especially for the purpose for which it is to be used, and is preferably well balanced and supported in a manner so that it is not affected by jars and vibration; a repeater relay RR and a pick-up relay PR which are similarly constructed, and a train control device K which may control the train in any suitable manner; but preferably comprises a device which allows a certain permissive speed depending on the control under which the train is at the time, the position of the train in the block, and the like.

Under normal conditions, as illustrated, the primary coil *P* of the car element on the right side of the vehicle facing in the direction of movement, that is, of the element R as shown in Fig. 2, is energized through a circuit which may be traced as follows:—beginning at the battery 38, wire 39, spring finger 40 of make-before-break contact 41, wire 42, winding of train control device K, wires 43 and 44, primary bus *p*, wire 45, blade 25, wire 46, primary coil *P*, wire 47, blade 26, wire 48 primary bus *p*, wire 49 back to the battery 38.

The energization of the primary coil P through the circuit just traced sets up a magneto-motive-force in the core 20 of the element which tends to send flux through the core and secondary coil S. On account of the reluctance of the large air gap between the pole pieces 21, very little flux passes through the secondary coil S. This magneto-motive-force is essential in the transmission of control influences, as will appear hereinafter; and in order to check the presence of current to produce this M. M. F., the normally energized train control device K has been connected in series therewith, so that failure of the circuit or a depletion of the battery to an extent to make the device unsafe, because of insufficient M. M. F., will cause the device K to drop to its deenergized position and thereby control the train in the same manner as if a knock-down control influence has been transmitted.

The repeater relay RR, which controls the primary circuit just traced, is normally energized through the following circuit:—beginning at the battery 50, wires 51 and 52, movable contact 53 of control relay D, front contact 54, wire 55, winding of repeater relay RR, wires 56 and 57 back to battery 50.

This latter circuit is controlled by the control relay D, which is normally energized by the following circuit:—beginning at the battery 50, wires 51 and 52, movable contact 53, front contact 58, wires 59 and 60, winding of the control relay D, wire 61, secondary bus 3, wire 62, blade 23, wire 63, secondary coil S, wire 64, blade 24, wire 65, secondary bus 3, wire 57 back to the battery 50.

The battery 50 is connected in the energizing circuit of the control relay D, so that the M. M. F. produced by the secondary coil S and the primary coil are cumulative. The M. M. F. produced by the secondary coil is, however, very small as compared to that produced by the primary coil, and is only incidental, in that, the current producing it is necessary to maintain the control relay energized.

The pick-up relay PR is connected in a circuit including the primary coil P and the secondary coil S of the lefthand element facing in the direction of movement, namely, the element L as illustrated in Fig. 2. When the primary and secondary coils are connected in series for pick-up purposes, they are so connected that a change of flux through the core of the car element will set up voltages in the circuit which are cumulative. This pick-up car circuit may be traced as follows:—beginning at the winding of the pick-up relay PR, wire 66, reset bus r, wire 67, blade 27, wire 68, primary coil P, wire 69, blade 28, wire 70, blade 29, wire 71, secondary coil S, wire 72, blade 30, wire 73, reset bus r, wire 74 back to the winding of the pick-up relay PR.

The current produced in the pick-up car circuit just traced due to a change of flux through the car element L under conditions as illustrated in Fig. 2, causes the pick-up relay PR to attract its armature, thereby closing its front contacts and completing an auxiliary energizing or pick-up circuit for the main control relay D, which circuit may be traced as follows:—from the battery 50, wires 51 and 77, front contact and movable contact 76 of the pick-up relay PR, wires 75 and 60, winding of the main control relay D, wires 61 and 62, blade 23, wire 63, secondary coil S of the car element R, wire 6, blade 24, and wires 65 and 57 to the battery 50.

Operation.—Assuming that a railway vehicle equipped with the apparatus in its normal condition as illustrated in Fig. 2 is moving along the track as illustrated in Fig. 1, and that it is passing over a track element KD in its open circuited condition. As the car element R moves over the track element KD, the reluctance through the core 20 of the car element will be momentarily reduced, thus causing a sudden increase of flux through the secondary coil S, partly due to diversion of flux from leakage paths, and partly due to an increase of the total flux through the primary coil, and then a sudden reduction of flux to its normal value. This change of flux generates in the secondary coil S of the element R a single cycle of E. M. F. similar to that of an alternating current. The first wave of this cycle of E. M. F., being due to an increase of flux, will by well-known principles of alternating current, be in a direction to oppose the voltage producing it and therefore will be opposed to the voltage of the battery 50, thus reducing the current through the winding of the main control relay D momentarily, thereby causing it to drop its armature permanently, because its energizing circuit is interrupted by its front contact 58. The deenergization of the control relay D opens the energized circuit for the repeater relay RR, which in turn interrupts the circuit through the train control device K. The deenergization of the train control device K will initiate suitable apparatus to control the speed of the train in any suitable manner, as heretofore explained.

It should be noted that the deenergization of the repeater relay does not interrupt the circuit through the primary coil P, which is in series with the train control device K when this train control device is deenergized. This is because the primary or exciting circuit is made through the back contact 78 of the make-before-break contact 41 and the wire 79 before it is interrupted through the front contact 40 of said make-before-break contact. Further, the primary coil P is magnetized by a much larger current when the control relay is deenergized than otherwise, this being due to the omission of the resist-

ance of the winding of the train control device K in this exciting circuit. This feature is very desirable, because the induction of current in the pick-up circuit is to a large extent proportional to the M. M. F. caused by the primary coil P, and therefore it is desirable to employ a high M. M. F. for pick-up purposes, this being automatically accomplished by the dropping of the control relay 10 D, at the time a pick-up impulse is required.

Assuming now that the train is proceeding through the block, limited in its travel by the control of the train control device K, and as it reaches the end of the block it passes 15 over the pick-up track elements PU connected in series, that is, in their clear or pick up condition. As the car element R passes over the pick-up element PU, the primary coil P causes a sudden increase of flux in the track 20 element PU. This flux immediately decreases to zero as the car element R recedes therefrom. This sudden building up and dying down of flux in the track element PU causes a single cycle of alternating current 25 to flow in the circuit connecting the two pick-up elements heretofore traced. This single cycle of alternating current sets up an alternating magneto-motive-force in the other pick-up track element PU. This alternating 30 magneto-motive-force will cause a change of flux through the track element PU, located on the left side of the vehicle when facing in the direction of movement, when in cooperative relation with the car element L, 35 thus inducing a current in the pick-up relay PR, which will cause its armature to be attracted, thereby closing the auxiliary pick-up circuit for the main control relay, thereby causing it to be again energized through the 40 stick circuit heretofore traced.

Assume now that a railway vehicle provided with the apparatus illustrated in Fig. 2 in its normal condition is passing over a knock-down track element KD having its coil 45 closed in a circuit of low resistance, as illustrated in Fig. 1. Under these conditions, no knock-down control influence will be transmitted to the control relay D. This is believed to be due to the fact that a rapid change 50 of flux through the track element KD is prevented by its coil being closed in a circuit of low resistance, this coil acting as a bucking coil tending to prevent a change of flux therethrough. Or in other words, as soon as a 55 slight increase of flux takes place, a current will be set up in the winding of the track element which, by well-known principles of induction, is in a direction to oppose the magneto-motive-force producing it. Since a 60 rapid change of flux is not permitted by the track element KD, no appreciable voltage will be generated in the secondary coil S of the car element R, thus allowing the control relay D to remain energized.

Assume now that the vehicle equipped with

the apparatus illustrated in Fig. 2 has been turned end for end, and is running tender first from left to right on the trackway illustrated in Fig. 1. Under these conditions, the arm 33 will be reversed, thereby moving each of the switch blades to the dotted position, as illustrated, thereby connecting the car element L which is now on the right side of the vehicle facing in the direction of movement, with its primary coil P to the primary bus p, which partial circuit may be traced as follows:—beginning at the primary bus p, wire 80, blade 27, wire 68, primary coil P, wire 69, blade 28, wire 81 back to the primary bus p; and connecting its secondary coil S to the secondary bus s, which may be traced by the following partial circuit:—beginning at the secondary bus s, wire 82, blade 29, wire 71, secondary coil S, wire 72, blade 30, wire 83 back to the secondary bus s. On the other hand, the car element R which is now on the left side of the vehicle facing in the direction of movement will be connected with its primary and secondary coils in series to the pick-up bus r by a partial circuit, which may be traced as follows:—beginning at the pick-up or reset bus r, wire 84, blade 23, wire 63, secondary coil S, wire 64, blade 24, wire 85, blade 25, wire 46, primary coil P, wire 47, blade 26, wire 86 back to the reset bus r.

If a train or vehicle, headed in the direction shown in Fig. 2, should reverse its direction of movement and travel opposite to the normal direction of traffic, the righthand car element R, formerly connected to the control relay D, is shifted over to the pick-up relay PR while the lefthand car element L is shifted over from the pick-up relay PR to the main control relay D.

Referring to Fig. 1 and imagining a train to be moving opposite to the normal direction of traffic indicated by the arrow, it can be seen that the knock-down track element KD at the entrance to each block, block I for example, may be open circuited and in the active 110 stopping condition due to the presence of a train in block J, and that the pick-up elements PU are individually included in a normally closed circuit of low resistance. The vehicle, traveling opposite to the 115 normal direction of traffic, has the coils of the left-hand car element L which passes over the knock-down track element KD, included in series in a deenergized circuit through the pick-up relay PR, so that no effect is produced on the car. Similarly, the car element which is connected to the main control relay D, passes over the right-hand pick-up element PU which has its coil 7 in a circuit of low resistance, so that no effect is produced upon the control relay D. The same analysis applies if the car shown in Fig. 2 were turned around, and should travel with the tender leading and in the normal direction of traffic. In short, no 120 125 130

control influences are communicated to a vehicle if it travels against the normal direction of traffic, and this desired end is accomplished automatically, without manual operation of any cut-out device or the like.

From consideration of the foregoing, it will be readily perceived that the same scheme of providing initiating and resetting impulses may be used in connection with 10 single track railroads as well as double track railroads, since the knock-down and pick-up track elements of each signal automatically provide the desired control for train movement in the direction governed by said signal, 15 so that any stretch of single or double track that is properly signalled may be likewise equipped with trackway devices for train control purposes in accordance with this invention, and permit movement of the vehicles 20 over these stretches of track in either direction and either end ahead, with the proper control influenced in each instance.

Inductive communicating apparatus for train control systems have thus been provided, in which car elements of identical construction are provided on opposite sides of a vehicle which are used for entirely different purposes at different times, and which are automatically transferred from performing 25 one function into circuits for performing another function automatically as the vehicle is changed end for end, that is, running tender first instead of pilot first, and vice versa. Also, these car elements are in one instance 30 connected in circuits which operate on the closed circuit principle and in another instance connected in circuits which operate on the open circuit principle, such circuits in each case being desirable, in that, the apparatus 35 will always be on the side of safety, that is, will stop the train when certain circuits fail, and will fail to give a clearing influence when other circuits fail.

While I have described only one specific 40 embodiment of my invention, I desire to have it understood that the specific embodiment shown and described is merely illustrative, and does not exhaust the adaptations and modification of means and functions constituting the present invention.

What I claim as new and desire to secure by Letters Patent, is:—

1. In an automatic train control system of 45 the type in which control influences are transmitted from the trackway inductively, traffic controlled influence transmitting means located along the trackway, a car element on one side of the vehicle connected on 50 the closed circuit principle for receiving knock-down influences, a similar car element on the other side of the vehicle connected on the open circuit principle for receiving pick-up influences, and means for interchanging 55 said car elements with respect to the circuits

when the direction of movement of the vehicle is changed.

2. In a train control system, a brake control device of the type which if initiated will continue to be effective until restored, means 70 for initiating said device located at one point on the vehicle, means for restoring said device located at another point on the vehicle, and means for interchanging the circuit connections of said two means when the direction of movement of the vehicle is changed.

3. In a train control system, a brake control device of the type which if initiated will continue to be effective until restored, means 75 for initiating said device constructed on the normally energized circuit principle including a car element, means for restoring said device constructed on a normally de-energized circuit principle including a similar car element, and means for interchanging said two elements in said circuits when the direction of movement of the vehicle is changed.

4. Car-carried apparatus for train control 80 systems comprising, an exciting winding for transmitting control influences, means for receiving a knock-down influence, means for receiving a restoring influence, said influences being dependent upon the energization 85 of said winding, and means for changing the excitation of said winding in accordance with whether a knock-down or a restoring influence is to be next transmitted.

5. Car-carried apparatus for train control 90 systems of the type in which control influences are transmitted inductively comprising, car elements each having independent windings, means for connecting said windings to independent circuits or connecting 95 them in series in a single circuit dependent upon the direction of movement of the vehicle.

6. In a train control system of the type in 100 which a brake control device if initiated will continue to be effective until restored, trackway means for initiating said device constituting an inert mass of iron when in its active condition, and having a winding connected in a circuit of low resistance when in its inactive condition; and another trackway apparatus for restoring said device comprising two inert masses of iron having windings connected in series in a circuit of low 105 resistance when in their active condition, and connected individually in circuits of low resistance when in their inactive condition.

7. In a train control system of the type in 110 which a brake control device is employed, which if initiated will continue to be effective until restored, means for controlling said device comprising, a car element having a primary coil and a secondary coil, another car element having coils thereon, and traffic controlled trackway means for transmitting 115

control influences from said primary to said secondary coil, and other traffic controlled trackway means for transmitting control influences from said primary coil to said another car element.

8. In a train control system of the type in which a brake control device is employed, which if initiated will continue to be effective until restored, trackway means for initiating said device constituting an inert mass of iron when in its active condition and having a winding connected in a circuit of low resistance when in its inactive condition; and other trackway means for restoring said device comprising two inert masses of iron having windings thereon which are connected in series in a closed circuit.

9. In an automatic train control system, the combination with automatic brake control apparatus on a vehicle acting upon the regular braking equipment thereof, and control means therefor adapted when conditioned for operation to continue in operation until restored, a source of electrical energy on the vehicle, an influence communicating device on the track energized from said source and effective only if a control circuit therefor is closed, means on the vehicle responding to the influence of the track device when effective for restoring said brake control apparatus, and trackway means for closing said control circuit for the track device when a predetermined portion of track in advance thereof is not occupied.

10. In a train control system, the combination with brake control apparatus on a vehicle rendered active when deenergized and automatically restored to the inactive condition when energized, cooperating car-carried receiving means and trackway influence means acting through an intervening air gap by electro-magnetic induction for energizing said apparatus, an energizing circuit for the track influence means, and car-carried means including a source of electrical energy for supplying current to said control circuit through an air gap.

11. Car-carried apparatus for train control systems comprising similar car-carried elements on opposite sides of the vehicle each having two windings, a normally energized circuit and a normally deenergized circuit, a source of current, and automatic means dependent upon the direction of movement of the vehicle for connecting one winding of one car element to said source, the other winding of that car element in the normally energized circuit, and the two windings of the other car element in series in the normally deenergized circuit.

12. Car equipment for train control systems comprising, brake control apparatus acting upon the regular braking equipment of the vehicle and requiring automatic restoration therof after each operation, a normal-

ly energized circuit adapted to initiate the operation of said apparatus, a normally deenergized circuit for restoring said apparatus, similar car elements on opposite sides of the car, and automatic means dependent upon the direction of rotation of the car axle for alternately electrically coupling said car elements to said circuits.

13. In a train control system, inductive influence communicating means for transmitting initiating and restoring influences comprising, elements along one side of the track and active when a control circuit therefor is broken for communicating the initiating influences, and elements arranged in pairs on opposite sides of the track and effective only if a control circuit therefor is closed for communicating a restoring influence.

14. In a train control system, the combination with initiating track elements on one side of the track, restoring track elements arranged in pairs on opposite sides of the track, car-carried elements on opposite sides of the car, control means on the car, and automatic means dependent upon the direction of rotation of a car axle for coupling said control means to the car elements automatically in accordance with the direction of movement on the vehicle and which end is leading.

15. In an automatic train control system, the combination of vehicle carried apparatus comprising a normally energized electrically operable control device which if momentarily deenergized will remain in its deenergized condition until restored, an inductive influence transmitting element, an inductive influence receiving element for restoring said electrically operable control device upon the reception of a control influence, and trackway apparatus for transmitting a control influence from the transmitting car element to the receiving car element only effective under clear traffic conditions ahead.

16. In a train control system for railroads having tracks divided into blocks, an initiating impulse device associated with each block and effective except when a control circuit therefor is closed, and restoring track devices arranged in pairs on opposite sides of the track and effective only if a control circuit therefor is closed.

17. Trackway apparatus for automatic train control systems comprising, a trackway divided into blocks each having a track relay, two trackway devices near the exit end of the block each comprising a core of magnetic material having a coil thereon, and means for connecting said coils in series in a closed circuit when the track relay of the next block in advance is energized, and for connecting each of said coils in a circuit of low resistance when said track relay of the next block in advance is de-energized.

18. Trackway apparatus for automatic

train control systems comprising, a trackway divided into blocks each having the usual track circuit including a track relay, two trackway devices near the exit end of each block each comprising a core of magnetic material having a coil thereon, means for connecting said coils in series in a closed circuit when the track relay of the next block in advance is energized, and means for connecting one of said coils in a circuit of low resistance when said track relay is deenergized.

19. Influence communicating means for automatic train control systems having suitable car-carried apparatus comprising, an inert trackway device for transmitting danger control influences to suitable car-carried apparatus including a trackway core of magnetic material having a coil thereon closed in a deenergized circuit of low resistance when in its clear traffic or inactive condition, and means for transmitting a clearing influence including two coils located along the trackway and connected in series in a closed deenergized circuit under clear traffic conditions ahead, whereby the failure of either of said circuits will not produce a false clear condition of the car-carried apparatus.

20. Influence communicating means for transmitting influences to a vehicle under clear traffic conditions to permit it to proceed less restricted comprising, a vehicle carried influence receiving coil connected to a normally deenergized electro-responsive device, a normally energized influence transmitting coil, and trackway means for transmitting a control influence from said influence transmitting coil to said influence receiving coil including two coils which simultaneously communicate with said influence transmitting coil and said influence receiving coil, respectively, means for connecting said coils in series in a closed circuit under clear traffic conditions ahead, and a further trackway device acting on said influence transmitting coil to initiate a brake application under unfavorable traffic conditions ahead.

21. An automatic train control system comprising, a control relay on a railway vehicle which if energized permits the vehicle to move unrestricted and having a stick circuit including a front contact of the relay and having a pick-up circuit, means partly on the vehicle and partly along the trackway for momentarily deenergizing said stick circuit including an inert trackway device, an energized vehicle carried inductor having a winding connected in series with said stick circuit and a plurality of normally energized circuits and devices, and means partly on the vehicle and partly along the trackway for momentarily closing said pick-up circuit including said energized vehicle carried inductor, an inert trackway device and a plu-

rality of normally deenergized circuits and devices.

22. An automatic train control system comprising, a control relay on a railway vehicle which if energized permits the vehicle to proceed unrestricted and having a stick circuit including a front contact of the relay and a pick-up circuit, means for momentarily deenergizing said stick circuit including an inert trackway device and a vehicle carried inductor having a winding connected in series with said stick circuit and a constantly energized winding connected in series with a brake control device, said circuit being so arranged that the opening of any one of these circuits will cause the transmission of a control influence, and means for momentarily closing said pick-up circuit including an inert trackway device and a plurality of circuits and devices so constructed that the opening of any one of said circuits will make this means ineffective to transmit a control influence.

23. An automatic train control system for railroads comprising, a normally energized control relay which if deenergized restricts the movement of the train and having a stick circuit including a source of energy and a front contact of the relay and having a pick-up circuit, car-carried influence receiving coils located differently with respect to the center line of the vehicle for momentarily deenergizing said relay and for momentarily closing said pick-up circuit respectively, a pair of inert trackway devices each having a circuit, one of said trackway devices being active only when its circuit is open and adapted to transmit a danger control influence to one of said car-carried coils to deenergize said relay, and the other trackway device being only active when its circuit is closed and adapted to transmit a restoring control influence to close said pick-up circuit, and means for interchanging the connections of said car-carried coils when the direction of movement of the vehicle changes.

24. An automatic train control system comprising, car-carried apparatus including a car element disposed on one side of the center line of the vehicle which element is adapted to receive a control influence when passing by a trackway device consisting of an inert mass of iron, but not adapted to receive a control influence when passing a similar mass of iron having a coil thereon closed in a circuit of low resistance, trackway devices spaced a similar distance on opposite sides of the center line of the vehicle each of said devices comprising an inert mass of iron having a coil thereon, and means for closing the coil of one of said trackway devices in a circuit of low resistance or opening said circuit when a vehicle is approaching said devices from one side depending upon whether traffic conditions ahead are clear of danger, and closing

the coil of the other device in a circuit of low resistance when a vehicle is approaching these devices from the other side, whereby no control influence can be transmitted when the vehicle travels against the normal direction of traffic.

25. Trackway apparatus for automatic train control systems comprising, a trackway divided into blocks by insulating joints each block having a track circuit including a source of energy and a track relay, means associated with each block for transmitting danger and proceed influences, respectively, comprising, an inert trackway device having a circuit, said device transmitting a danger control influence to suitable car-carried apparatus if said circuit is open but being incapable of transmitting a control influence if said circuit is closed, an inert trackway device for transmitting proceed influences including a circuit, said device being capable of transmitting a proceed influence if said circuit is closed but being incapable of transmitting a control influence if said circuit is open, and means governed by said track relays to close the circuit of said first mentioned trackway device if the first block in advance of the block with which said transmitting means is associated is unoccupied, and for closing a circuit of the second mentioned trackway device if the block with which said transmitting means is associated is unoccupied.

26. An automatic train control system comprising, a car-carried element having a normally energized flux producing winding and an influence receiving winding, an electro-pneumatic brake control device connected in series with said flux producing winding, and means for discontinuing the flow of current through said electro-pneumatic device without interrupting the flow of current through said flux producing winding when an inductive influence is received by said influence receiving winding.

45 27. An automatic train control system comprising, a car-carried element including a magnetic core having a normally energized flux producing winding, an electro-pneumatic brake control device connected in series with said flux producing winding, and means for shunting said electro-pneumatic device when a danger inductive influence is received.

28. In an automatic train control system, a vehicle and a track therefor divided into blocks each provided with a normally closed track circuit, separate influence devices associated with each block and adapted to transmit to a passing vehicle distinctive control influences, a deenergized circuit for the rear influence device of each block controlled separately by the track circuit of that block and closed when the track circuit is unoccupied, and another deenergized circuit for the advance influence device of each block controlled separately by the track circuit of the

next block in advance and closed when said next block is unoccupied.

29. In an automatic train control system, a vehicle and a track therefor divided into blocks, automatic train control apparatus on the vehicle, a stick relay for governing said apparatus, and separate influence devices associated with each block and controlled separately by the track circuit of different blocks for selectively influencing the pick-up and the stick circuits of said stick relay, said influence devices each having a coil closed in a deenergized circuit under clear traffic conditions ahead.

30. An automatic train control system for railroads comprising, a normally energized control relay which if deenergized restricts the movement of the train and having a stick circuit including a source of energy and a front contact of the relay and having a pick-up circuit, car-carried influence receiving coils located equal distances on opposite sides of the center line of the vehicle for momentarily deenergizing said relay and for picking up said relay respectively, a pair of trackway devices each having a circuit, one of said trackway devices being active only when its circuit is open and adapted to transmit danger influences to deenergize said relay, and the other trackway device being active only when its circuit is closed and adapted to transmit a proceed influence to restore said relay, and means for interchanging the connections of said car-carried coils for different directions of movement of the vehicle.

31. An automatic train control system of the type in which distinctive danger and proceed inductive influences are transmitted from the trackway to the vehicle comprising, a normally energized stick relay having a stick circuit and a pick-up circuit, an energized inductor having a winding connected in series with said stick circuit and cooperating with trackway devices to momentarily de-energize said stick circuit under danger traffic conditions, a normally deenergized relay having a front contact connected in said pick-up circuit, and means for momentarily energizing said last mentioned relay from said energized inductor under clear traffic conditions.

32. In an automatic train control system, vehicle carried apparatus for controlling the movement of a train including a control relay having a stick circuit and a pick-up circuit, an energized inductor located outside the center line of the vehicle and having a winding connected in series with said stick circuit, a second inductor located outside the center line of the vehicle and having a winding connected in series with a device for closing said pick-up circuit, traffic controlled trackway means for influencing said energized conductor to momentarily de-energize said stick circuit under danger traffic conditions and for

- transmitting energy from said energized inductor to said second inductor and momentarily energizing said pick-up circuit under clear traffic conditions, and means including
- 5 a member operated when the direction of movement of the vehicle is changed for permitting the reception of said influences from said trackway control means if the vehicle is turned end for end and is traveling in the
- 10 normal direction of traffic.
33. An automatic train control system comprising, a vehicle carried stick relay having a stick circuit and a pick-up circuit, a source of energy on the vehicle, and means
- 15 for opening the stick circuit of said relay comprising traffic controlled trackway devices and a single energized vehicle carried inductor having a coil connected in series with said stick circuit, and means for energizing the pick-up circuit of said relay by a device energized from said energized vehicle carried inductor through controlled trackway devices.

In testimony whereof I hereby affix my
25 signature.

CHARLES S. BUSHNELL.
